UNITED STATES PATENT OFFICE.

ERNEST H. HERRSTRUM, OF MOLINE, ILLINOIS.

DIVIDERS AND CALIPERS.

Application filed February 6, 1922. Serial No. 534,395.

To all whom it may concern:

Be it known that I, ERNEST H. HERRSTRUM, a citizen of the United States, residing at Moline, in the county of Rock Island and State of Illinois, have invented 5 certain new and useful Improvements in Dividers and Calipers, of which the following is a specification.

This invention relates to dividers, calipers and similar instruments, and has for 10 its principal object to permit them to be folded into a compact form that will occupy a minimum of space.

Heretofore locking devices for securing 15 the legs of these instruments in adjusted position have been more or less rigidly fixed to one leg so as to extend beyond the other leg, whether the instrument was in folded or extended condition. It is therefore 20 another object of my invention to provide locking means that can be folded with the legs and will lie substantially within the width of the legs.

Another object of the invention is to provide 25 an improved micrometer adjustment for giving the legs the exact position desired after they have been locked in approximately that position.

Further objects of the invention will be 30 apparent as the description is read in connection with the accompanying drawing showing a selected embodiment of the invention in which—

Fig. 1 illustrates an elevation of a pair 35 of dividers embodying the invention; and

Fig. 2 is a transverse section on the line 2—2 of Fig. 1.

I have shown the invention as applied to 40 dividers, but the application to similar instruments will be clear to those skilled in the art.

In the drawings, 10 and 11 indicate legs 45 of a pair of dividers hinged at 12 and provided with suitable points 13 and 14. The leg 10 is provided with a guide 15 substantially rectangular in form, in which a block 16 is adapted to reciprocate under the control of a thumb-screw 17 passing through the block and swiveled to the leg 10. As

50 here shown, the screw has a shoulder 18 adjacent to the head and is upset at 19 on the inside of the leg 10, and a spring 20 serves to take up any slack in the construction. The block 16 is provided with a pinte 55 21 upon which is pivoted a link 22 having a short arm 23 and a long slotted arm

24. The short arm is preferably of a length to reach from the right edge of the leg 11 to the extreme position of the pinte 21 to the left in Fig. 1. The slotted arm is sufficiently long to permit full extension of the legs of the dividers and is slidably connected with the leg 11 by a thumb-screw 25 which preferably passes through the leg 11 and has a shoulder 26 to lie against the arm 24 on opposite sides of the slot 27.

In use, when it is desired to extend the dividers, the thumb-screw 25 is loosened and the legs spread apart to the approximate distance and the screw 25 tightened. Then the screw 17 is turned in the appropriate direction to give the points 13 and 14 the exact nicety of adjustment required. The movement of the block 16 under the action of the screw 17 permits the legs to be given a relative movement by a very slow motion that enables the operator to very accurately set the dividers or other instrument to which the invention is applied, and the spring 20 takes up any lost motion that may be in the parts and secures the parts in the position of adjustment. When the instrument is to be put away, the screw 25 is loosened and the legs and link moved from the position indicated in dotted lines in Fig. 1 to approximately the position shown in solid lines in Fig. 1 when the long arm of the link will lie on the leg 11 and the short arm will lie across the legs substantially as illustrated. The invention, therefore, makes it possible to fold the instrument very compactly so that it will occupy much less space than the construction now in common use, and the micrometer adjustment will enable the accurate setting of the points 13 and 14, and serve to hold them securely in the adjusted position.

90 The guide 15 reinforces the leg 10 and makes it possible to extend the slot for the block 16 well into the leg and thereby provide ample movement for the block 100 within a very narrow instrument.

I am aware that changes may be made in the form, construction and arrangement of the invention, as set forth in the selected embodiment herein, without departing from the scope or sacrificing any of its material advantages, and I therefore reserve the right to make all such changes as fairly fall within the scope of the following claims.

I claim:

110 1. The combination of a pair of legs hinged together, a link having a long arm

- provided with a longitudinal slot and a short arm at an angle to the long arm, means for pivotally and adjustably connecting the short arm to one leg, and adjustable means carried by the other leg and co-operating with the slotted arm to secure it thereto, said long arm being adapted to lie within the width of the two legs when the legs are brought into closed positions.
- 10 2. The combination of a pair of legs hinged together, a link having an arm substantially equal to the width of the two legs and a long slotted arm at an angle thereto, means for pivoting the short arm to one leg, and means for slidably connecting the slotted arm to the other leg, said slotted arm being adapted to lie within the width of the two legs when the legs are brought into closed positions.

3. The combination of a pair of legs 20 hinged together, a guide on one of said legs, a block slidable in said guide, a screw swiveled to said leg and engaging said block, a link pivoted to said block and having an angular slotted arm, and means for securing 25 said slotted arm to the other leg.

4. The combination of a pair of legs hinged together, a guide extending transversely to one of said legs, a block slidably mounted in said guide, a spring resisting 30 the movement of said guide in one direction, a screw swiveled to said leg and engaging said block, a link pivoted to said block and having an angular slotted arm, and means for securing said slotted arm to the other 35 leg.

ERNEST H. HERRSTRUM.
